UNITED STATES PATENT OFFICE.

EDWARD J. SCHUH, OF SPOKANE, WASHINGTON.

CONCRETE-TAMPING MACHINE AND METHOD.

Application filed November 7, 1927. Serial No. 231,702.

The object of this invention is to provide an improved method and mechanism for tamping concrete and similar compositions and the invention is especially adapted for the manufacture of bricks, blocks and like useful articles made therefrom.

One feature of the invention consists in imparting to a given area of concrete a succession of tamping impacts in rapid following relation, one upon the other, so that the material acted upon will not only be more dense but also more uniform.

In this connection, where a mold is employed, it is a feature of the invention to use a tamper of reduced cross section with respect to the interior of the mold so that under the action of quick successive tamping, the material will be not only reduced to a maximum and uniform density immediately under the tamper, but the latter will drive the excess material laterally so that various forms of interior configuration of molds can be uniformly filled.

In a more specific phase of my invention, I employ a tamper with a means coacting therewith to obtain in one single stroke of the tamper, a plurality of tamping impacts, and preferably, one impact is obtained through one character of agency and other impacts through another character of agency.

My invention involves an actuating means that operates through a fixed and predetermined cycle, in combination with a floating cross head and a floating tamper and gravity means.

Other features and objects of the invention will be more fully described in connection with the accompanying drawings and will be more particularly pointed out in and by the appended claims.

In the drawings;

Fig. 1, is a view in elevation of my improved tamping mechanism.

Fig. 2, is an edge elevation thereof with the parts in an elevated or starting position.

Fig. 3, is a similar view showing the position of the parts in that initial movement just prior to tension of the springs.

Fig. 4, is a similar view showing a further movement after the springs have been tensioned.

Fig. 5, is a final position after the tamper has reached the mold.

Fig. 6, is a vertical sectional view on line 6—6 of Fig. 1, looking to the left, showing the

parts in a position similar to that shown in Fig. 3.

Fig. 7, is a view similar to Fig. 6, showing the parts in a position similar to Fig. 5.

Like characters of reference designate similar parts throughout the different figures of the drawings.

As shown, the device of my invention includes a frame having similar side members 1 connected at their upper ends at 2 and having a suitable supporting base 3. The frame is shown provided with any suitable character of mold supporting shelf 4 upon which a mold 5, is shown. I have not detailed any means for centering the mold in a predetermined position on the shelf as my invention does not pertain to such features and further, such details are within the skill and common knowledge of this art.

Reference will first be made to my improved actuating means which operates through a fixed and predetermined cycle of movement.

A power shaft 6, is journaled in suitable bearings 7, in frame members 1, and on one end of said shaft is a crank 8, connected with a link 9. On the remaining end is a crank 10, connected with a link 11, the crank 10 having a crank handle 12, suitable for the application of manual power although mechanical power may be of course applied. The links 9 and 11 are connected at their upper ends with what I will call actuating shoes, both of which are alike in structure and function and only one of which need be described in detail, the same reference letters being applied to both.

The frame members 1 are each provided with a slide-way in the form of a slot 13 which may be of a single width throughout its height from the top 14 to the bottom 15. The shoe comprises a shank 16, extending through the slot and a relatively short guide 17, on the inside of member 1, and a relatively long guide 18, on the outside of member 1, whereby the shoe is held to a fixed path of reciprocation. The elongation of the outer guide 18, is partly to afford adequate bearing surface and partly to form an actuating end and abutment for a cross head which will be presently described. Projecting from the exterior of the shoe is a link boss 19, to which the respective links 9 and 10 are pivoted in order to impart reciprocating movement to the shoes as a result of rotation of the crank or

power shaft 6. Said boss 19, has a reduced shank 20 which may be provided with a nut 21', for an operative connection with the cross head next to be described.

5 I will next describe the cross head that is operated by the heretofore described actuating means.

My cross head is designated at 21 and may be, as shown, of uniform cross section and of a length sufficient to span the frame members 1 and project therethrough with the ends 22 extending beyond said members 1, as shown. Said cross head may be provided with inside flanges 23, adapted to slide along the inside faces of frame members 1, to hold the cross head against lengthwise movement therein and in a horizontal position. The ends 22, are shown provided with studs 24, having nuts 25. Said cross head is operatively connected with the actuating means, preferably yieldingly, by springs 26, the same being tension springs, having their ends 27 and 28, respectively, connected with studs 20 and 24, as shown. The cross head 21, is actually floatingly mounted in the frame, in the sense that it partakes of movement of a variable nature with respect to the movement of the actuating means to which it is operatively connected. When in the starting position shown in Fig. 1, the cross head rests upon the abutments 29, which are formed by the upper ends of guides 18. In this position, the parts are so arranged and proportioned that the springs 26, are not under tension but they perform the useful function of insuring descent of the cross head with the actuating means in the event that friction or other imperfections of the parts tended to retard gravity descent of the cross head. Thus 40 while the springs 26 are not under any tension, preferably, in the Fig. 1, position, they do form a connecting means functioning positively. However, where the machine is in good working order and properly made, the importance of this function of the springs 26, would be of a secondary nature.

Reference will next be made to my improved tamper and the manner in which it is mechanically associated with the cross head.

50 My improved tamper consists, as shown, of a relatively heavy body portion 30, which will preferably be made of metal and will be of sufficient weight to readily seek by gravity any position which it is free to assume. The cross section of the tamper body 30, will be designed and proportioned in accordance with the size mold employed. In the drawings, I have shown the tamper to be of a cross section less than the interior of the mold 5, to afford clearance all around of a greater extent than a mere working clearance. Said tamper body 30, is reduced to form a shank 31, the reduction forming what I will term an impact shoulder 32, for a useful purpose that will presently be described. The shank

31, is provided with a slot 33, which is slidably associated with a centrally reduced portion 34, of the cross head 21, as clearly shown. This slot 33, having a length greater than the major cross section of the cross head, affords 70 the tamper some relative movement independent of the cross head whereby it will be seen that the tamper is floatingly connected with the cross head. A further reason for the length of the slot will be later described. 75

One of the agencies for obtaining a plurality of concussive impacts with a single tamper stroke, will next be described.

80 A weight is indicated at 35 and the latter is associated with the tamper by being slotted as shown at 36, for slidable projection therethrough of the shank 31. Functionally, the association of the weight and tamper relates more particularly to the fact that the weight 35 coacts with the impact shoulder 32, of the tamper. The weight 35, is floatingly associated with the tamper and means is provided for supporting the weight and restricting its action on the tamper to a predetermined period of operation, which means I 90 will next describe.

95 Bars 37, are rockably mounted at their opposite ends in frame members 1 and are shown supported on their lower edges 38, in suitable openings 39, in said frame. The shape of the openings is clearly shown in Fig. 2, and the walls of the openings serve to limit rocking movement of the bars from weight supporting to weight releasing positions, and vice versa. Means such as springs 40, interposed between the outer ends of the bars and suitable abutments 41, normally urge said bars 37, into a weight supporting position. The upper edges 42, of said bars serve for direct engagement with the end portions of weight 35, as will be clearly seen in Fig. 6. I will next revert back to the shoes, and to Fig. 2, wherein it will be seen that I have provided the outside guides 18, with cams 43. As the shoes descend, these cams 43, wedge the upper edges of the bars 37, outwardly, as will be seen in Fig. 4, to release the weight 35. On ascent of the shoes, the cams 43, will readily pass between the bars 37, by forcing them apart, the spring returning the bars to 110 again restore them into a position to support the weight. 115

I will next describe the operation of the device and the method of my invention.

120 In the starting position shown in Fig. 1, the links 9 and 11, support the shoes in an uppermost position and the shoe abutments 29, support the cross head 21, in an uppermost position. The weight of the tamper will normally cause the latter to assume the position shown, by gravity, but in any event, the weight 35 would limit upward movement of the tamper beyond the Fig. 1, position. The weight 35, is supported in the Fig. 1, position, by the bars 37. As shown in Fig. 6, only a 125

small amount of concrete is disposed in the mold 5, and concrete will be gradually fed into the mold to an increasing depth until the mold is slightly overfilled. I have not shown a feeding means as the latter is not a part of this invention. However, in my Patent No. 1,581,814, issued April 20, 1926, entitled Machine for making concrete products, there is shown and described a feeding means 10 that would be advantageously adapted for use in connection with my present tamping device. In this patent, the tamper is smaller in cross section than the interior of the mold so that the mud is tamped not only downwardly but also laterally.

The initial downward movement from the position shown in Figs. 1 and 2, is illustrated as being partly completed in Figs. 3 and 6, in the former of which the cross head 21 is still supported by the abutments 29, and in the latter of which the cross head has advanced into engagement with the weight 35. After the cross head 21 has engaged the weight 35, further movement of the cross head 25 is temporarily arrested and as the shoes further descend, the springs 26 will be tensioned, as shown in Fig. 4. In this latter position, the shoes have descended sufficiently further to tension the springs 26 and the cams 30, 43, are just about in a position to actuate the bars 37. After the cams 43, have actuated the bars 37, the weight 35, will be released and just as soon as weight 35 is released, then the springs instantly contract thereby imparting a very sudden and powerful downward impulse to the cross head 21. The cross head 21, will follow the weight 35 and remain in engagement therewith because the rate of speed of descent of the cross head 21, under 40 the action of the contracting springs 26, will be sufficient to cause the cross head to maintain the same relation with respect to the weight 35 for a limited extent of travel. Of course, the tamper will also descend with the 45 cross head and weight.

At this point I desire to draw attention to a very important feature which can readily be seen by reference to Fig. 6. It will be noted that the lost motion between the bottom of the cross head 21 and the bottom of slot 33, is many times less than the distance between the bottom of weight 35 and the impact shoulder 32. Now as the parts descend, the tamper 30, will first strike the concrete, which will be the initial impact of the downward stroke of the tamper. This will arrest the tamper, or rather stop further downward movement thereof. The descending cross head will next strike the bottom of slot 33, and this will constitute the second impact of the single downward stroke. Immediately after the cross head has struck the tamper, the weight 35 will strike shoulder 32, and this will constitute the third impact of the one 60 and single downward stroke of the tamper.

Now it will be clear that even though the initial impulse of the cross head is imparted to the weight 35, before it is imparted to the tamper, and even if the weight 35 is actually above the tamper, still, because of the slight 70 lost motion between the bottom of the cross head and the bottom of slot 33, as compared to the far greater distance between the bottom of weight 35 and shoulder 32, it will be clear 75 that the cross head will impact onto said tamper before the weight does.

Fig. 4, illustrates the exterior parts in the position where the bars 37 are just about to be actuated to release the weight 35, and at such point, the cranks 8 and 10 are nearly to the 80 dead center point of the first half of revolution of the shaft 6. When the tamper strikes the concrete, irrespective of the extent of fill of the mold, the cross head 21 will be free from engagement with the abutments 29, so that the springs 26 will be free to exercise their full strength in imparting a downward 85 thrust to the cross head 21. It will be clear that if the abutments 29, arrested the cross head 21, before the tamper 30 struck the concrete, that such interference would rob the tamper of the full force of its tamping blow. Hence, by reference to Fig. 5, it will be seen that there is a clearance between the 90 abutments 29 and the cross head 21 and that the springs 26 are still tensioned by reason of the fact that the cranks 8 and 10 have reached a lower dead center position, and the 95 springs have yielded in order that the cranks could negotiate the lower turn. A corresponding position showing the interior parts, 100 is illustrated in Fig. 7.

Now as the shaft 6, continues in a clockwise direction, viewing Fig. 7, the springs 26, will first be slackened and then the abutments 29 will engage the cross head 21 and lift the latter. This lifting of cross head 21 will take up the lost motion between the top of cross head 21 and the top of slot 33, as shown in Fig. 7 and the tamper and weight 110 will be elevated to the initial position, as will now be clear from the foregoing position. The bars 37, will first be spread to let the cams 43 pass, and will immediately thereafter be returned by springs 39, to the Fig. 2, position. 115

It will now be clear that because the springs 26 are under tension when the tamper strikes the concrete, initially, that the tamper cannot rebound, but will be held to its position of impact with the concrete throughout the period during which the cross head 21 and weight 35, successively strike the tamper.

Concrete mud is very sluggish material to feed, especially to feed rapidly, and further, it requires thorough tamping. Now it has always been a problem to effectively tamp concrete as rapidly as it could be fed, and I have solved the problem, not by increasing the actual rate of speed of the tamper, which 125 would be objectionable, but by the novel 130

method and mechanism whereby in one single downward stroke of the tamper, three distinct impacts are made on the same area of material, namely, the concrete.

5 It will be clear that the springs 26, initially impart the downward thrust to the weight 35, but after the cross head strikes the tamper, then, the remaining fall of the weight 35 into engagement with shoulder 32, is by gravity.

10 Of course this gravity movement of the weight is very greatly accelerated by the momentum initially imparted to the weight by the springs 26.

15 By reason of the difference in the lost motion connection between the cross head and the tamper, on the one hand, and the difference in spaced relation of the weight 35 with respect to the shoulder 32, on the other hand, I can carry out the device of my invention 20 with the operation herein disclosed, irrespective of the difference in weight as between the tamper 30, and weight 35.

25 It will be understood that while I have used the term "concrete" throughout the specification and claims, that this term is used generically to cover like or similar compositions, such for instance as magnesite, saw-dust and cinders, where a suitable binder is inherently or additionally present.

30 It is believed that the invention will be clearly understood from the foregoing description, and while I have herein shown one specific form of my invention, I do not wish to be limited thereto except for such 35 limitations as the claims may import.

I claim:

40 1. In a concrete tamping machine, a frame having a shelf adapted to support a mold, a horizontally disposed cross head floatingly disposed vertically in said frame toward and away from said mold, a vertically disposed tamper having a reduced shank providing an impact shoulder and said shank having lost-motion slotted connection with said cross head, a tamper impact weight slidable on said shank between said shoulder and cross head, retaining bars rockingly mounted in said frame and normally supporting said weight against downward movement and acting through said weight to limit downward movement of said cross head and tamper, power actuated shoes slidable vertically in said frame and having upper cross head actuating portions for positively elevating said cross head tamper and weight, springs connecting said shoes with said cross head for imparting downward movement to the latter, and cams on said shoes for rocking said bars to release said weight after initial movement of said shoes has tensioned said springs, whereby said tamper will first strike the concrete and said cross head will next strike said tamper and finally said weight will strike said tamper.

45 2. In a concrete tamping machine, a frame

having a shelf for supporting a mold, a cross head floatingly slidable in said frame, a tamper having an impact shoulder and having lost motion connection with said cross head, a tamper impact weight for engagement with said shoulder, retaining members normally retaining said weight against downward movement and acting through said weight to arrest downward movement of said cross head, power actuated shoes slidable in said frame and positively engaging said cross head to elevate the latter, and springs connecting said shoes with said cross head to impart quick downward movement to the latter, and cams on said shoes for actuating said members to release said weight after initial movement of said shoes has tensioned said springs, thereby impelling movement of said tamper against the concrete and subsequent movement of said cross head and weight against said tamper, respectively. 70 75 80 85

3. In a concrete tamping machine, a mold, a tamper therefor, spring means impelling said tamper, and gravity means for impacting on said tamper after the latter has engaged the mold contents. 90

4. In a concrete tamping machine, a mold, a tamper therefor, means impelling said tamper, and means impacting on said tamper after the latter has engaged the mold contents. 95

5. In a concrete tamping machine, a mold, a tamper therefor, and mechanism imparting successive tamping concussions to said tamper in one tamping stroke of the latter. 100

6. In a concrete tamping machine, a mold, a tamper therefor, a normally supported weight associated with said tamper, and mechanism applying spring tamping propulsion to said tamper and releasing said weight for impact against said tamper after the latter has engaged the contents of said mold. 105

7. In a concrete tamping machine, a mold, a tamper therefor, a weight associated with said tamper, means for arresting tamping movement of said weight and tamper, and mechanism having an initial movement for imposing tamping stress on said tamper and a concluding movement for actuating said means to release said weight and tamper to first engage said tamper with the mold contents and subsequently permit said weight to impact on said tamper. 110 115

8. In a concrete tamping mechanism, a frame supporting a mold, a floating cross head slidable in said frame, a tamper having lost motion connection with said cross head, actuating shoes having a fixed cycle of movement in said frame and provided with abutments for elevating said cross head, and springs connected with said shoes and cross head for causing initial engagement of said tamper with the mold contents and subsequent engagement of said tamper by said cross head. 120 125 130

9. In a concrete tamping mechanism, a frame, a mold thereon, a floating cross head 5 slidable in said frame, a tamper having lost motion connection with said cross head, for tamping concrete in said mold of increasing depths, and means yieldingly connected with said cross head for imparting tamping movement to said tamper.

10. In a concrete tamping machine, a frame, a mold thereon, a cross head slidable in 10 said frame, a tamper having lost motion connection with said cross head, means for resisting tamping movement of said tamper, and mechanism yieldingly connected with 15 said cross head for actuating said tamper and releasing said means.

11. The herein-described method of tamping concrete, which consists, in imparting an impact thereon and in subsequently imposing 20 a series of concussive blows on the same impacted area of concrete in one tamping stroke.

12. In a concrete tamping machine, a frame, a mold thereon, a cross head slidable in 25 said frame, a weight subjacent and close to the bottom of said cross head, a tamper body subjacent said weight and having a weight impact shoulder in spaced relation below said weight, said body having a shank in lost motion connection with said cross head of a 30 reduced extent with respect to the extent of spaced relation between said weight and shoulder, and means for actuating said cross head downwardly to first engage said tamper with the concrete and thereby take up the 35 lost motion between said cross head and tamper and cause the former to strike the latter and said weight subsequently engaging said shoulder, thereby insuring a triple tamping impact in one tamping stroke. 40

In witness whereof I hereunto affix my signature.

EDWARD J. SCHUH.
